SELECTIVE MULTICOLOR PENCIL

Walter E. Jacobsen and Walter H. Jacobsen,
Churchville, Pa.

Application July 7, 1947, Serial No. 759,392

4 Claims. (Cl. 120—14.5)

1

Our invention relates to a pencil which can be used to write in any of a number of colors, at the will of the user.

Heretofore, pencils have been constructed to write in more than one color, but in general they have been bulky, difficult to operate, easily damaged, and expensive to manufacture.

It, therefore, is an object of our invention to provide a pencil capable of writing in a wide range of colors, and which is slender, sturdy, easily manipulated, and of inexpensive construction.

Another object of our invention is to provide a single pencil of the character described which can substitute for a box of colored crayons.

Another object of our invention is to provide a selective, multi-color pencil which is easily re-loaded, and which provides an indication of the color in use, and of the other colors available.

Other objects of our invention are to provide an improved device of the character described, that is easily and economically produced, which is sturdy in construction, and which is highly efficient in operation.

With the above and related objects in view, our invention consists in the details of construction and combination of parts, as will be more fully understood from the following description, when read in conjunction with the accompanying drawing in which:

Fig. 1 is a side view of a multi-colored pencil embodying our invention.

Fig. 2 is a top view of the pencil of our invention illustrated in Fig. 1 with the hood removed.

Fig. 3 is a partly sectional top view of our invention, showing the inner chamber and lead-carriers contained therein.

Fig. 4 is a side view of our invention from which the barrel and lead-carriers have been disassembled.

Fig. 5 is a side view of the barrel head and the operating slide mounted upon a coaxial shaft.

Fig. 6 is a side view of one of the lead carriers used in our invention.

Fig. 7 is a transverse section taken along the lines 7—7 of Fig. 1.

Fig. 8 is a transverse section of the chamber taken along the lines 8—8 of Fig. 4.

Fig. 9 is an end view of the assembly shown in Fig. 5, the view being taken along the line 9—9 of Fig. 5.

Fig. 10 is a side sectional view of the colored lead selector assembly without the lead carriers.

Fig. 11 is a partly sectional side view of the

selector assembly with a carrier in the fully retracted position.

Fig. 12 is a partly sectional side view showing the operating slide in engagement with a carrier, ready to extend the carrier.

Fig. 13 is a partly sectional side view showing the operating slide in engagement with a carrier, with the carrier partly extended.

Referring now to the drawings, wherein the same reference characters designate the same parts, we show a pencil, consisting of a barrel, generally designated as A, a hood, generally designated as B, a revolvable chamber, generally designated as D, an operating slide, designated as E, a plurality of colored-lead carriers, each designated as F, a color index cap G, and a barrel head, designated as H.

The lead carriers F, one of which is illustrated in Fig. 6, are long narrow members made of flat stock having a short extension 16 offset at one end. The other end 18 which is broader than the body of the carrier has a small slot 20 whose walls cooperate with a shoulder 21 on the barrel head H, as will be described presently. A short piece of flexible tubing 22 is supported upon the offset end 16 of each carrier, and the tubing in turn receives and supports a single colored lead 24.

As shown in Figs. 7 and 11, the carriers F, when not extended for use, lie substantially within longitudinal slots 26 of the revolvable cylinder D. The cylinder D comprises a long, cylindrical member having a central bore 28 and a plurality of longitudinal slots 26 which extend from one end 29 of the chamber to the other end 30. The bore 28 is reduced in diameter for a short length 31 at the end 30 of the chamber to lock with the end 35 of the shaft 34. The slots 26 are of a width sufficient to accommodate the lead carriers F already described.

The cylinder D, the barrel head H, and the colored index cap G are mounted upon the shaft 34; however, the barrel head H and the colored index cap G are rigidly attached to rotate in unison with the shaft 34 while the cylinder D has relatively free rotation about the shaft. The cylinder D and its barrel A rotate in unison. The operating slide E also rotates about the shaft 34 but it is controlled to rotate when it is in the narrow slot in the barrel head H.

The cylinder D comprises a cylinder having a series of equally spaced chambers 26 extending parallel to its longitudinal axis. The chambers 26, adjacent the end 29 extend completely in a radial direction through the cylinder and midway along the longitudinal axis of the cylinder.

the slots 26 become shallow so that a lead carrier may rest in the slot. The operating slide is adapted to move within the completely slotted end of the cylinder D in order to push the lead carrier F along the chamber 26 in which it is nestled.

As shown in Fig. 10, a slender metal shaft 34 extends through the bore 28 of the chamber D and is firmly attached at one end 36 to the length 31 of the chamber. The other end 38 of the shaft is rigidly attached to the color index cap G. The color index cap G has a number of depressions 40 spaced around the circumference thereof, equal in number and aligned with the chamber slots 26. These depressions 40 are filled with various colors which colors may indicate the colors of lead carried in the corresponding chamber slots 26. The cap G is also provided with knurling 44, to facilitate the rotation of the cap by the user, and the cap may also be adapted to hold an eraser 46.

As shown in Figs. 4 and 5, a cylindrical barrel head H is rotatably mounted on the axial shaft 34, between the color index cap G, and the open end 29 of the revolvable cylinder D. That portion 42 of the barrel head which is adjacent to the cylinder is reduced in diameter, and is provided with an annular shoulder 21 at its extremity.

As shown in Fig. 11, when a lead carrier F lies within a cylinder slot 26 in retracted position, the shoulder 21 of the barrel head is seated within the slot 29 of the carrier.

As shown in Figs. 11 and 13, the barrel head H is provided with a bore 48 which extends approximately half the length of the barrel head, commencing from the shoulder end thereof. The wall which bounds the bore 48 has a single longitudinal slot 50. The slot 50 and the bore 48 are adapted to accommodate the C-shaped operating slide E. A short pin 52 is fixed in the solid portion of the barrel head, and this pin helps to lock the barrel head H to the barrel A, as will be described later.

The operating slide E, shown in Fig. 5, consists of a C-shaped member with a cylindrical bottom 63, which bottom encircles the axial shaft 34. The lower horn 64 of the operating slide has the same outline as the section of the shoulder 21, as illustrated in Figs. 10 and 12. The aperture enclosed by the C-shaped member E forms an eye 76, in which a wedge member C operates, as will be described later.

As shown in Figs. 2 and 7, the barrel A of the pencil comprises a long hollow cylindrical member, which member is externally threaded at one end 54 to secure the hood B thereto. A long narrow slot 56 is located in the wall of the barrel A, and this slot extends from the unthreaded end of the barrel along the greater part of the barrel's length and is open at the other end.

As shown in Fig. 3, the hood B of the pencil has a cylindrical end 60 which is internally threaded to screw upon the threaded end 54 of the barrel, and from the cylindrical end 60 the hood B tapers conically as at 61 to a small round aperture 62 through which aperture the writing lead projects. Since the pencil of our invention is refilled with new leads 24 from the point end of the barrel, the hood B is adapted to be easily unscrewed from the barrel. Knurling 66 is provided on the hood for this purpose.

The assembly of the parts and their functioning is as follows:

The axial shaft 34 serves as a mounting upon

which are located the rigidly secured color index cap G, the rotatable barrel head H, the movable operating slide E, and the rigidly secured chamber D. The operating slide may be introduced into the barrel head slot 50, in which location it remains together with the barrel head when shaft 34 is revolved. In addition, when the barrel head slot 50 is aligned with any particular chamber slot 26, the lower horn 64 of the operating slide E becomes engaged with the carrier F lying in that particular slot. The operating slide may then be moved longitudinally along the chamber slot 26 so as to extend the carrier. The aforementioned action is illustrated in Figs. 10, 11, 12 and 13.

A lead carrier F is located in each chamber slot 26, each carrier having its slot 20 engaged by the shoulder 21 of the barrel head. Each carrier supports a single colored lead by means of a short piece of flexible tubing 22. One end of the tubing is slipped upon the extension 16 of the lead carrier and the other end of the tubing is slipped over an end of the colored lead 24. Since the offset extension 16 of the carrier is directed toward the longitudinal axis of the pencil, the leads 24 are but slightly displaced from this axis, as shown in Fig. 3. When a lead carrier is extended, the lead 24 is guided by the conical wall 81 of the tip hood through the central aperture 62, the flexible tubing 22 bending as required.

When the described subassembly is inserted with the barrel A, the operating slide E projects through the longitudinal slot 56 in the barrel. In addition, the fixed pin 52 in the barrel head projects into a circular enlargement 57 of the slot 56. A metal retaining band J fits tightly over the cap end of the barrel, locking the barrel slot and the pin 52 in engagement. An index mark 68 is provided on the band J, which mark should be aligned with the slot 50 in the barrel head when the band is affixed over the barrel.

As shown in Fig. 7, a wedge member C is provided on the exterior of the barrel A for the purpose of locking the carrier in position when the desired length of the colored lead tip is exposed. The wedge consists of a short section 70 of a ring, the outer circumference 72 of which section is eccentric with the inner circumference 74. This ring section 70 extends through the eye 76 contained by the exposed portion of the C-shaped operating slide, and the ring section is provided with a small block 78 at each end to prevent the loss of the wedge. When the wedge C is revolved about the barrel in the proper direction, clockwise as viewed in Fig. 7, the enlargement of the ring section causes the wedge to clamp against the barrel, and against the top of the eye 76 of the operating slide E, locking the carrier at that point. To release the carrier, the wedge is rotated in the opposite direction, whereupon the enlarged portion of the wedge is removed from engagement with the barrel and the operating slide.

To prepare the pencil for writing with any desired color of lead contained in the pencil, the user rotates the color index cap G until the depression 40 which bears the desired color is in registry with the index mark on the band. The operating slide is then moved toward the point end of the pencil, the slide traveling within the selected slot of the cylinder, until the lead projects from the tip aperture the desired length. The operating slide is then locked at this posi-

tion, using the wedge for the purpose in the manner described.

To reload the pencil, the hood B is removed, the empty carrier F is extended and a new length of colored lead is inserted in the tubing support.

Although we have shown the pencil as having a structure for receiving and writing with six differently colored leads, it is obvious that the pencil might be constructed to contain more or fewer leads as wished.

Although our invention has been described in considerable detail, such description is intended as being illustrative rather than limiting, since the invention may be variously embodied, and the scope of the invention is to be determined as claimed.

We claim as our invention:

1. In a multi-color pencil having a plurality of lead carriers, a barrel, a cylinder within said barrel, a shaft about which said cylinder rotates, an operating slide having an eye encircling said shaft and movable along said shaft, said cylinder having a plurality of chambers each of which receives a slide for holding a length of lead, a color index cap, a barrel head, said cap and said barrel head being rigidly attached to said shaft, said operating slide enveloping said metal shaft whereby said slide may move one of said lead carriers, and said cap and barrel head being adapted to rotate said slide whereby one slide may be moved along its complementary chamber.

2. The invention of claim 1 including means to lock said operating slide in a predetermined position.

3. The invention of claim 1 including wedge means for locking said operating slide at any desired degree of extension.

4. A multi-color pencil, comprising a barrel, a point hood, a cap and a shaft revolvable axially in unison within said barrel, a cylinder affixed to said shaft and free to rotate about said shaft, a plurality of lead carriers, means in said cylinder for receiving said carriers, a single operating slide movably mounted upon said shaft and being adapted to optionally engage only one of said lead carriers, means for indicating the particular lead carrier in engagement with said operating slide at any time, and wedge means for locking said operating slide to said barrel at any point within the travel of said operating slide.
